LIQUID FUEL SUPPLY SYSTEM

Wayne S. Schoepbach, Mount Morris, Mich., assignor to General Motors Corporation, Detroit, Mich., a corporation of Delaware

Filed Jan. 17, 1964, Ser. No. 338,516
3 Claims. (Cl. 222—386)

This invention relates to a fuel system and more particularly to a liquid fuel system including a supply tank adapted to serve an internal combustion engine spaced from the tank.

A difficulty has been experienced in the use of automotive vehicles in that if a car is parked on a hill facing down the incline and the engine is stopped, the fuel supply line is apt to act as a siphon and continue the flow of fuel from the supply tank to the engine possibly to flood the intake manifold and the combustion chambers and cause liquid fuel to leak into the crankcase.

One object of the present invention is to provide a fuel system in which siphoning from a supply tank to an engine will be prevented subsequent to stoppage of the fuel pump.

One feature of the present invention is a fuel supply system having a pump closely associated with a fuel supply tank and having a connection from the pump controllable by the pump pressure to open a supply line and by spring means together with the static pressure in the tank to close the supply line.

These and other important features of the invention will now be described in detail in the specification and then pointed out more particularly in the appended claims.

In the drawings:

FIGURE 1 is a partial view of components making up a fuel system in which the present invention is embodied; and

FIGURE 2 is an enlarged and sectional view of a portion of a fuel pump illustrated in FIGURE 1.

The drawings show a fuel tank 10 containing gasoline 12 and having an opening 14 in its top through which is suspended a gasoline pump 16. This pump advantageously may be of the type described in the United States Patent 2,968,248, granted January 17, 1961, in the name of Robert L. Carter. This pump has a screened inlet 18 such as indicated at 18 which is arranged closely to approach the bottom of the tank 10. It will be appreciated, however, that other forms of the pump could be utilized in practicing the present invention.

The pump 16 has a bottom portion 20 and an intermediate portion 22 between which is interposed a sealing gasket 24. The portions 20 and 22 are not shown in detail as their details do not form a part of the present invention but it suffices herein to state that the two portions 20 and 22 cooperate in defining a pump discharge conduit 26 leading to a pump outlet connection generally indicated at 28.

The outlet connection 28 is formed with two ports 30 and 32. These ports are axially aligned although not necessarily so. The port 30 is surrounded by a lip 34 facing the interior of the outlet connection 28 and communicates with a discharge line 36 leading to a carburetor 38 serving an internal combustion engine.

2

The port 32 is formed in a circular disk 40 which is welded as at 42 to the cylindrical wall of a cylinder or chamber 44 formed in the pump portion 20. Slidable in the cylinder 44 is a piston valve 46 of inverted cup formation and having a circular surface 48 facing the lip 34 and positioned to open or close the port 30 with the lip 34 serving as a valve seat. Spring means in the form of a coil 50 is positioned between the disk 40 and the piston valve 46 constantly urging the latter toward its closed position against the lip 34.

In operation, the pump 16 will be forcing gasoline through the discharge conduit 26 to the outlet connection 28. The pressure of the fluid discharged from the pump acts upon the surface 48 of the piston valve 46 thereby compressing the spring 50 and permitting the gasoline to be discharged by way of the line 36 to the carburetor 38.

If the system is on a vehicle which is parked facing downhill and the pump 16 serving the engine is stopped, the fuel flow through the line 36 would tend to continue because of the siphoning action heretofore referred to but with the use of the present construction the termination of the fuel pump pressure causes the piston valve 46 to be balanced insofar as static pressures are concerned and the spring 50 then becomes effective to close the port 30 and prevents any siphoning action.

I claim:

1. A liquid fuel supply system for an engine, said system comprising a tank, a pump having an inlet connected with the interior of said tank and an outlet connection, said outlet connection having two ports, a discharge line connected to one of said ports, a piston valve slidably mounted in said outlet connection and interposed between and separating said two ports, the other of said two ports being connected to a low zone of said tank interior, spring means urging said piston valve to close said one port, and the arrangement being such that said spring means is adapted to yield under discharge pressure of said pump.

2. A liquid fuel supply system for an engine, said system comprising a supply tank, a pump having an inlet and an outlet connection in said tank, said outlet connection having one port leading from said tank and one other port leading into a low zone of said tank, a piston valve arranged to open and close said one port and constantly to close said one other port, and spring means urging said piston valve to close said one port.

3. A liquid fuel supply system such as set forth in claim 2, said piston valve being larger than said one port in diameter whereby pressure developed by said pump is adapted to move said piston valve to compress said spring means and open said one port.
